ELASTIC BINDING FOR FOOTWEAR

Robert T. Dawes, Hudson, Mass., assignor to
 Thomas Taylor & Sons, Inc., Hudson, Mass., a
 corporation of Massachusetts

Application July 1, 1940, Serial No. 343,325

3 Claims. (Cl. 36—57)

This invention pertains to footwear, and relates more particularly to an improved elastic tape or webbing for use as a finished binding at the top edge of a shoe upper. While for many years past it has been customary to insert gores of elastic webbing in shoe uppers, particularly at the sides of men's shoes of the Congress type, the practice of making large portions or indeed substantially all of a shoe upper from elastic material is of comparatively recent origin, at least as applies to the manufacture of fine shoes for women's wear. However, at the present time many shoes, particularly those of the pump type, have uppers which are largely of stretchable elastic material; for instance, elastic webbing having its outer surface finished or covered to provide any desired and acceptable appearance.

In the manufacture of shoes of the "Congress" type it has long been recognized that the upper, exposed edge of the inserted elastic gore is prone to become permanently elongated during wear so as to lose the desired close fit, and to overcome this difficulty goring having reinforced edges has recently been introduced. However, the trade practice in making women's shoes has been to provide a finish bead, commonly known as a French cord or English cord finish, at the top edge of the upper, and this established practice must be followed by the shoemaker even though the shoe upper be in part or wholly elastic. Since it is an essential feature of a shoe having a stretchable upper that its top edge be capable of elongation, it has heretofore been proposed to use a French cord binding of elastic material, that is to say, a tape or the like including rubber threads. However, ordinary elastic webbing having the desired external appearance and thinness to form an acceptable French cord edge does not possess sufficient elastic strength to withstand the effects of repeated donning and doffing of the shoe, and soon becomes permanently stretched, thus imparting a slovenly appearance to the shoe, the difficulty becoming more and more pronounced as the elastic area forms a larger and larger part of the shoe upper. In the attempt to overcome this difficulty, shoemakers have resorted to the practice of applying a second or additional tape arranged at the inside of the upper just below the top edge, such tape being elastic but thicker and heavier than the tape which it is permissible to use in forming a French cord edge. This second tape not only assists in maintaining the desired degree of elastic resiliency at the edge, but may also help in imparting the proper contour to the top portion of the upper. Obviously, however, this use of two separate elements, to wit, the French cord finishing tape and the inner

reinforce tape, necessitates the preparation, handling and attaching of two separate pieces of material, thus involving a considerable item of expense in making the shoe.

The present invention has for its principal object the provision of an elastic tape which can be used in substitution for both the prior elastic French cord edge finishing tape and the secondary or reinforce tape which has commonly been applied independently to the inside of the shoe upper, such improved tape providing all of the advantages flowing from the use of the independent French cord and reinforcing tapes previously employed but reducing the time and cost of application as well as decreasing the amount of material required. The improved tape or webbing, in accordance with the present invention, comprises two integrally joined, longitudinally extending distinct strips, which preferably differ in width and in elastic properties and which are preferably separated by a longitudinally extending indentation or groove which defines the fold line and facilitates uniform application of the binding to the upper. Both strips comprise uniformly spaced rubber warp strands bound together by textile yarns, some of the textile yarns being warp yarns. The rubber threads which are employed, are all of substantially the same size and elasticity, thus facilitating the weaving of the material, but, on the other hand, in the narrow finishing strip which is designed to be exposed at the outer side of the shoe upper, each rubber warp strand consists of single rubber thread, whereas in the wide reinforce strip which is designed to be disposed at the inside of the shoe upper and which performs the function of the previously employed independent reinforce tape, each elastic strand comprises a group of elastic threads. For example, two such threads may be arranged side-by side, either widthwise of the material or one on top of the other thicknesswise of the material to constitute each elastic strand. The textile warp strands are uniformly spaced throughout the width of the binding except that at the fold line some of these textile warp threads are omitted, thereby creating a thinner area.

The accompanying drawing illustrates this invention with particular reference to the employment of the elastic binding in the manufacture of women's shoes.

In that drawing,

Fig. 1 is a perspective view of a shoe embodying this invention;

Fig. 2 is an enlarged diagrammatic cross-sectional view, taken along the line 2—2 in Fig. 1, of the binding employed as a French cord edging in a shoe;

Fig. 3 illustrates the first step in attaching the

binding to form the edging shown in Figs. 1 and 2;

Fig. 4 is a view similar to Fig. 2 illustrating the binding employed as an English cord edging;

Figs. 5 and 6 are cross-sectional views illustrating the formation of woven bindings embodying this invention;

Fig. 7 is a diagrammatic plan view of a helically woven or braided tape;

Fig. 8 is a diagrammatic section on the line 8—8 of Fig. 7;

Fig. 9 is a diagrammatic section, similar to Fig. 4, but illustrating a modification; and

Fig. 10 is a view generally similar to Fig. 9, but showing a further modification.

The shoe 10 includes expandible and contractible panels 11 and is provided at the top edge with a finish 12 embodying this invention. As shown particularly in Figs. 2 and 3, the finish 12 is formed of a binding 15 comprising an outer strip 16 and an inner strip 17 united at a fold line 18. The binding 15 is secured in the form of a French cord edging, the outer strip 16 being attached by stitches 19. The panels 11 each consists of an elastic gore 20 and an outer facing 21 of fabric.

The binding 15, as shown in Fig. 5, comprises rubber warp strands 25 and fabric warp threads 26 bonded by fabric weft threads 27. The rubber strands 25 in the strip 16 consist of single threads of rubber and in the strip 17 of two threads of rubber, so that the amount of rubber per unit of width in the latter strip is twice that in the former strip. The omission of the fabric warp threads 26 between the strips 16 and 17 forms the fold line 18. The rubber threads forming the strands 25 in the strip 17 are arranged one on the other transversely of the thickness of the fabric so that the strip 17 is thicker than the strip 16.

The binding 15' in Fig. 6 differs from the binding 15 in that the double rubber threads forming the strands 25' in the strip 17' are disposed side by side widthwise of the fabric so that the strips 16' and 17' are of the same thickness. The binding 15' includes the fold line 18', and the warp strands 25' and threads 26' are bound together by weft threads 27'.

It will be noted that in each form of binding the rubber threads forming the warp strands are of the same size so that the tension thereon may be uniform during the weaving of the bindings with the result that the longitudinal edges of the tape are of substantially uniform length and the tape is straight and substantially devoid of tendency to curve in its own plane. The amount of rubber, however, is greater in the strip which is designed to be secured to the inner wall than in the other strip.

Fig. 4 illustrates the use of the binding 15 to make an imitation French cord or English cord edging which differs from the edging shown in Fig. 2 merely in the manner in which the strip 16 is secured to the outer face of the shoe.

Figs. 7 and 8 illustrate a tape embodying the invention but of braided or helically woven type. In this material the textile yarns 26^x and 27^x extend diagonally across the tape as results for example from making the tape upon a braiding machine, while the rubber strands extend longitudinally of the tape and substantially parallel with its selvage. As in the tape of Fig. 5, the elastic strands in the portion 16^x (Fig. 8) of the tape are single rubber threads, while each

elastic strand in the part 17^x consists of a plurality of rubber threads, all of the rubber threads being of substantially the same elasticity. At the section 18^x the elastic strands are omitted, thus producing a thin area which defines a fold line.

Fig. 9 illustrates the application of the improved tape in a manner which is the reverse of that shown in Fig. 4; that is to say, the thicker portion 17 of the tape is disposed at the outside of the upper 11 while the thinner part 16 of the tape is arranged at the inside of the upper. For such use the outer surface of the part 17 may be of an ornamental weave or may be woven with inclusion of distinctively colored yarns or yarns of different materials so that the part 17 provides an attractive collar constituting a finish for the top of the upper. The arrangement of Fig. 9 provides a finish of the English cord type but reversed, and it is to be understood that a similar reversal of the usual French cord construction will also provide the suggested collar effect. In Fig. 9 the tape is shown as having a fold line at 18 but in Fig. 10 a similar arrangement is shown wherein the tape is unprovided with a distinctive fold line.

While the forms of elastic binding herein shown and described are woven, it will be understood that the invention is not limited thereto and that the bindings may be made by other methods, e. g. braiding—but in any event the invention contemplates the provision of an elastic binding including two strips, one of which strips differs from the other in that it has a greater amount of rubber or other elastic material per unit of width and hence is more resistant to stretching forces exerted longitudinally.

I claim:

1. An elastic binding and reinforcing tape for use in binding the raw edge of a shoe upper, comprising a narrow fabric having two integrally joined longitudinally extending portions of different thickness, each said portion being of substantially uniform thickness throughout its width and containing longitudinally extending rubber warp strands, the thicker portion of the tape having a greater resistance to longitudinal stretch than does the thinner portion.

2. An elastic binding and reinforcing tape for use in binding the raw edge of a shoe upper, comprising a narrow fabric having two integrally joined longitudinally extending portions of different thicknesses, each said portion being of substantially uniform thickness throughout its width and containing longitudinally extending rubber warp strands, the thicker portion of the tape having a greater resistance to longitudinal stretch than does the thinner portion and being composed of rubber strands which are multiples of the rubber strands in the thinner portion.

3. An elastic binding and reinforcing tape for use in binding the raw edge of a shoe upper, comprising a narrow fabric having two integrally joined longitudinally extending portions of different thicknesses, each said portion being of substantially uniform thickness throughout its width and containing longitudinally extending rubber warp strands, the tape having a structural fold line intermediate said portions and the thicker portion of the tape having a greater resistance to longitudinal stretch than does the thinner portion.

ROBERT T. DAWES.
